See Jackson. Design for Fire Place Grate Frame

James & Sonners

in York

Aug 20 1847

Patented May 15 1847.

Des. 121

James S. Jackson. New York, New York.
Letters Patent (Design No. 121.) dated 15th May, 1847.

The schedule referred to in these Letters Patent and may
King part of the same.

To all whom it may concern: Be it known that I, James S. Jackson, of the City of New York, in the County and State of New York, have produced a new design for a "Fire Place Grate," which he does not know or believe to have been known or used prior to his production thereof.

To enable those skilled in such matters to make my design I will describe the construction, reference being had to the

Des. 121.

numerous drawings making a part of this specification.

This is a Grate in three parts, viz. A Frame, a Summer piece and a Fender.

The Frame This consists of a series of heavy scroll and leafage, with shell work in combination with other figures, in the Louis XIV. of France style of Architecture.

I provide a scroll, as (a) for a centre of the frame; and from this I proceed to the right and left with a series of figures one corresponding to the other on each opposite side. By a reference to the drawings it will be seen that from the scroll (a) towards each side are a continued succession of scrolls, shells and leafage, extending to and forming a bracing upon the blank centre (d) which centre is flanked on its outside by shells and leaves (c). The two right and left sides of this frame conform to each other by corresponding figures, and the above completes the top of the frame. The two sides of the frame may be seen as follows: On the inner side is a series of shells upon a flat ground work; to this, next outward is added a scroll which is followed by a dolphin, entwined with a series of scrolls, the head of the dolphin being towards the bottom, and being up on a plain base or a plain base foundation piece.

The Summer Piece. - This is in the same style of architecture as the Frame and is a flat ground with a series of scrolls (g) encircling the outside, and immediately inside of this is a set of shell work (h); and this again terminates on a set of scrolls (i); thereof, the whole being founded upon a base of scrolls (i). (A) is a plain flat centre but directly over this in some cases I intend to place a Phoenix or other ornament, (A') by means of bolts or rivets the same being in high relief upon the centre of the Summer Piece.

(d') is a cluster of flowers and is intended in like manner to be placed in high relief upon the flat (d) of the frame.

The fender. - This is in a lighter style, more like that of Louis XV. It consists of a plain moulding base (K) upon which are

121

raised posts (m) and upon these over the centres of the moulding a plain round rod (o) the whole forming a semi circle, and a vine (p) entwines the rod with its ^{septors and} leaves, dropping between the rod and the base,

Having thus fully described my production, and referred to the drawing, what I claim as my production and desire to secure by Letters Patent is the peculiar configuration here set forth for a "Fire Place Grate" consisting of a "summer piece", a "frame" and "fender", as well as the high relief ornaments, the whole being described and to be used in cast metal, for the above purpose.
